UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR WORKING UPPERS OVER LASTS.

Application filed June 27, 1919. Serial No. 307,061.

To all whom it may concern:

Be it known that I, BERNHARDT JORGENSEN, a subject of the King of Denmark, residing at Beverly, in the county of Essex and State of Massachusetts, have invented 5 certain Improvements in Machines for Working Uppers Over Lasts, of which the following description, in connection with the accompanying drawings, is a specification, like reference characters on the drawings indicating like parts in the several figures.

This invention relates to machines for working uppers over lasts, and in respect 15 to certain features has more particular reference to machines for operating upon the upper at the end portion of a shoe. The invention is herein shown as embodied in a machine having means for pulling an upper over the toe end of a last and for working the upper into lasted position and fastening it at the toe; but it will be understood that the invention, in many of its features, is not limited to a combination of 20 means for performing these several operations nor restricted in utility to toe lasting.

One object of the invention is to provide an improved construction adapted for use in the manufacture of a well known type of 25 shoe which is made of felt. In the manufacture of shoes of this kind it is a common practice to cut the upper of sufficient size to permit it wholly or partially to overlie the bottom of the last in place of an insole and, 30 before the shoe is mounted on the last, to stitch the opposite side edges of the upper either directly together or to an inserted piece of similar material extending for a 35 portion at least of the distance lengthwise 40 of the shoe. The stock is then dampened and a last is inserted, thus stretching and forming the material in the desired shape. The best results in the shaping of the shoe, however, require that the bottom edges of 45 the material at the toe portion of the shoe be left free and unsecured until after the last has been inserted and that the toe portion of the upper be shaped to the last by a subsequent lasting operation.

50 The operation of lasting the toe of such a shoe must be performed with due regard to the conditions resulting from the preceding steps in the manufacture of the shoe and

from the character of the material of which the shoe is made. One characteristic of the 55 felt, particularly when dampened for the purpose of lasting, is its tendency to tear readily if an undue strain is applied at any point, and another characteristic is the tendency for the gathered folds in the margin 60 of the upper to react and spring up from the bottom of the last after the lasting pressure has been released. It is of particular importance, however, in this kind of a shoe, 65 that the upper be retained in a substantially 70 flat condition for a considerable distance inwardly from the edge of the last bottom, since otherwise there is danger that in the subsequent upper trimming operation preparatory to the application of the sole the 75 overlaid margin of the upper may be cut too close to the edge of the last bottom and thus weaken the seam whereby the upper and the sole are subsequently stitched together. It is also essential that the operation 80 of pulling the upper over the toe of the last, which is required for the best results in the shaping of the shoe, and the operation of laying or wiping the margin of the upper 85 inwardly over the last be so performed as to avoid distorting the previously shaped upper at the rear of the toe or crowding the margin of the upper backwardly at the sides in such manner as to produce objectionable wrinkles in or adjacent to the previously 90 shaped portion. A machine designed to deal with the conditions encountered in 95 lasting such shoes is shown and described in Letters Patent No. 1,413,589, granted on my application on April 25, 1922, and it is one 100 object of the present invention to provide improvements in the type of machine there disclosed. Among its more particular objects this invention has in view the provision of means for securing improved results 105 when operating on shoes which are comparatively wide and blunt across the toe, means for improving the lasting along the sides of the toe, and means for insuring regularity in the gathering of the margin of the upper and effectiveness in securing it in a substantially flat condition over the margin of the bottom surface of the last.

With the above and other objects in view, the invention provides, among its important 105 features, a novel construction and arrange-

ment of means for gathering and wiping the margin of the upper inwardly round the end of the shoe. The construction shown comprises a pair of end embracing wiper plates mounted to close inwardly over the bottom of the last, and an additional pair of wiper plates which close inwardly at the sides between the shoe and said first plates and receive a substantial movement inwardly beyond the inner edges of the first plates after the latter have completed their gathering and overwiping operation. For convenience the first mentioned pair of plates will be hereinafter frequently referred to as "end" wipers and the additional pair as "side" wipers, although it will be evident by reference to the accompanying drawings that in the illustrative construction the end plates are substantially coterminous in rearward extent with the side plates. The side plates are so mounted as to close inwardly beyond the end plates without any component of rearward movement lengthwise of the shoe and, in fact, with a substantial component of forward movement of their inner wiping edges toward the toe end of the shoe, whereas the end plates have a substantial component of movement rearwardly as they close, and the side plates are thus effective in their inward movement beyond the edges of the end plates to correct any condition that may result from the tendency of the end plates to crowd the material rearwardly along the sides of the shoe. The machine shown includes in its organization a novel arrangement of means whereby the end plates are closed by the action of mechanism engaging the end face of the shoe and the side plates receive their effective movement from operating members which move laterally of the shoe and push these plates inwardly over the shoe independently of the end plates. Still further to insure regularity in the gathering of the margin of the upper, with a view for example to location of the upper securing fastenings at the most effective points with relation to the gathered folds, the wipers are so constructed as to determine with precision the location of the folds, this object being effected in the illustrative construction by means including a notched or recessed formation of the edges of the wiper plates particularly designed to localize the folds. A further feature of the invention consists in a novel combination of means for working an upper over a last and means for fastening the margin of the upper in position. Combined with means for gathering the margin of the upper in outwardly directed folds disposed in predetermined locations as hereinbefore explained, the invention in its illustrative embodiment provides means for driving fastenings substan-

tially in line with or over said folds in the best position for preventing reaction of the gathered material. In the construction shown, which is designed to form three forwardly directed folds and an outwardly directed fold at each side located farther rearwardly, three tacks are driven substantially at the front of the gathered material in line with the forward folds and two additional tacks are disposed farther rearwardly and in line with the rear folds, i. e., with the several tacks located substantially at the lines of greatest convexity of the respective folds. In order to determine with accuracy the location of the tacks with relation to the material gathered by the wipers, the tackers are positioned by the wiper mechanism, all five of the tackers being mounted for movement lengthwise of the shoe with the wiper support and a pair of tackers at each side being mounted for movement also laterally of the shoe with the corresponding side wiper plate. The tacking means comprises a construction and arrangement of tack holders, tack drivers and operating mechanism particularly designed to co-operate with the overworking means for the purposes in view, and additional features of the invention are to be recognized in details of the combination thus provided.

Still another feature of the invention consists in novel work positioning means, the construction shown providing a three-point bearing for the bottom of the shoe so arranged as to determine with precision the relation of the toe end portion of the shoe to the overworking means. More particularly, the illustrative construction comprises a forepart shoe rest provided with members arranged to engage the bottom of the shoe at two points only in locations spaced laterally of the shoe, and an additional member mounted on the usual heel rest for engaging the bottom of the shoe at the heel end, with provision for varying the position of the shoe with respect to movement about a longitudinal axis by relative adjustment of the forepart engaging members and for varying the lengthwise inclination of the shoe by relative adjustment of the heel rest member and the forepart members. Such an arrangement of shoe positioning means is of particular advantage in a machine provided with automatically operating toe lasting mechanism, since the pressure of the wipers on the different portions of the work may be precisely determined for the size and style of shoe with the assurance of uniform results on all shoes of that size and style.

The above and other features of the invention, including certain details of construction and combinations of parts, will now be described with reference to the ac-

companying drawings and pointed out in the claims.

In the drawings,

Fig. 1 is a view in side elevation and partly in vertical section of the head portion of a pulling over and toe lasting machine in which the invention is embodied;

Fig. 2 is a view in side elevation on a larger scale and at a slightly different angle of a portion of the toe lasting mechanism shown in Fig. 1;

Fig. 3 is a detail view at a different angle of a portion of the wiper operating means seen in Fig. 2;

Fig. 4 shows in elevation the wipers and the tacking devices as viewed from the rear;

Fig. 5 is an inverted plan view showing the wiper mechanism, the toe gripper and a portion of the side wiper operating means;

Fig. 6 is a detail perspective view showing a portion of the tacking mechanism detached;

Fig. 7 is an exploded view showing portions of one of the tack holders and its support;

Fig. 8 is a view substantially in plan of the wiper mechanism, showing the end wipers at the limit of their overwiping movement and the side wipers at an intermediate stage in their inward movement;

Fig. 9 is a view similar to Fig. 8 showing the parts at the end of the overwiping operation and illustrating the location of the tacks and

Fig. 10 is a detail view of a portion of the wiper and stacker operating means.

The machine in which the invention is herein shown as incorporated includes in its general organization features of a well-known type of pulling-over machine shown and described in prior United States Letters Patent No. 1,029,387, granted on June 11, 1912, upon an application of R. F. McFeeley, and more particularly in respect to

the toe lasting means embodies many of the features shown and described in my prior Patent No. 1,413,589. In view of these prior disclosures, which may be referred to for a more complete understanding of the details of construction of the machine, the present description will be limited to such details as it is necessary to refer to for an understanding of the novel features of this invention.

For positioning the work the machine has a shoe bottom rest which is mounted for swinging movement as usual in machines of this type and includes a member 2 mounted for adjustment in directions lengthwise of the shoe and pivotally supporting at its front end a shoe rest plate 3. Mounted in the plate 3 are a pair of studs 4 for engaging the shoe stock on the bottom of the last in locations spaced laterally of the shoe, these studs being each adjustable in the plate

transversely of the plane of the shoe bottom. A spring 5 located between the rear end of the plate 3 and a portion of the shoe rest tends to swing the plate in a direction to carry its front end upwardly, and an adjustable limit stud 6 carried by the plate and arranged to bear on a portion of the rest serves to determine the normal position of the plate with respect to movement about its axis. The machine has also a cam 8 on a cam shaft 10 for swinging the shoe rest downwardly in the upper pulling operation, a heel rest 12 which is moved upward into supporting and positioning engagement with the heel end of the shoe after the machine is started, and side clamp devices 14 which are swung inwardly into supporting and holding engagement with the forepart of the shoe after the upper pulling operation. Like the machine shown in my prior patent, the upper pulling means of the present machine comprises only a toe gripper which, in the present construction, has jaws 16 curved as shown in Fig. 5 for engagement with a substantial extent of the margin of the upper round the toe end of the last, this construction being particularly well adapted for wide shoes. The jaws 16 are mounted on a gripper casing 18 and are operated to grip and to pull the upper by means of a gripper bar 20 connected to an updraw lever 22 which is operated yielding through a spring 24 by a cam slide 26 to which operative movement is imparted by a cam 28 on the cam shaft 10. The normal position of the toe gripper lengthwise of the last is determined by a slide 30 provided, as shown in Fig. 1, with a roll in engagement with the rear face of the gripper bar 20, the gripper being held by the slide against the tension of overdraw springs 32 in position to receive the margin of the upper when the shoe is presented to the machine.

In front of the toe gripper the machine has means for gathering and wiping the margin of the upper over the bottom of the last and for driving tacks to secure the upper in lasted position, the wiping and tacking means being supported on a front arm 34, which is mounted to swing lengthwise of the last about a center 36. Operative rearward movement is imparted to the arm 34 by means of a slide 38 which is engaged and operated by a pinion 40. Like the machine shown in said prior patents, the present machine is designed to perform its cycle of operations in successive stages or steps between which the machine comes automatically to rest, although the invention in many of its features is not limited to a machine having this particular characteristic. When the machine is first started the toe gripper is operated to grip and pull the upper, accompanied by a slight downward rocking movement of the shoe bottom rest,

and the machine then comes to a stop with the upper held under tension to permit an inspection of the work and any adjustment which the operator observes to be necessary. 5 When the machine is again started the side clamping and supporting devices 14 are swung into operative engagement with the shoe, and either immediately, or after a second period of rest in the cycle, the toe gripper 10 is swung rearwardly to overdraw the margin of the upper and the wiping and tacking mechanisms are operated to wipe the margin of the upper inwardly and to fasten it in lasted position. The rearward movement of the toe gripper and of the front arm 34 takes place in consequence of retractive movement of the slide 38 to which the front arm is connected, this slide carrying a lug 42 which controls the slide 30 by 15 engagement with a lug 44 on a rack bar 46 connected to the slide as described in detail in Patent No. 1,029,387. As the front arm 34 is swung rearwardly, the toe gripper is thus released to the action of its overdraw 20 springs 32 and permitted to swing over the last bottom, the gripper being finally tripped and caused to release the upper by engagement of the front arm 34 with a latch 48 on the gripper. In the continued movement of the arm 34 the wipers are advanced and closed over the shoe, and after the gathering and wiping operation has been completed the tacks are driven to fasten the upper, as will be hereinafter described more 25 in detail.

The wiper mechanism comprises a wiper supporting member 50 secured by means of a clamp screw 52 on the lower end of the front supporting arm 34, the screw 52 extending through a slot 56 in the member 50 to permit the latter to be adjusted lengthwise of the last in such manner as to determine the correct limit of lengthwise movement of the wipers relatively to the shoe. 40 Mounted on a pivot 58 on the support 50 are a pair of wiper plates 60, herein termed "end" wipers, the pivot 58 being located at such a distance from the operative front edges of these wipers that they swing about 45 an axis which is positioned beyond the end face of the shoe when they are at their limit of operative movement, as shown in Fig. 8, the purpose of this arrangement being to cause all portions of the wiper edges to receive a substantial component of movement laterally of the shoe during their movement lengthwise of the shoe in order to assist in gathering the margin of the upper inward laterally of the shoe and in avoiding objectionable displacement lengthwise of the last of portions of the margin near the opposite side edges of the shoe bottom. For imparting operative movement to the wipers 60 the support 50 carries a slide 62 to 55 which is secured adjustably by means of a

clamp screw 64 a bar 66 carrying upon its front end a pad 68 for engagement with the toe end face of the shoe. The outer end of the slide 62 is arranged to engage a pair of levers 70 which are pivotally mounted on the support 50 and are connected by means of links 72 to ears 74 which project rearwardly from the wiper plates 60. Springs 76 connected to the levers 70 tend to hold the levers in engagement with the slide 62 and to position the slide at its forward limit of movement determined by engagement of the inner end of the screw 64 in a slot 78 in the support 50. The parts are thus held normally by the springs 76 with the end 80 wipers in open position, as shown in Fig. 5. The connections between the links 72 and the wipers include provision for adjustment in the manner more fully shown and described in my prior patent. 85

In addition to the wipers 60, the present machine is provided with wiper plates 80, herein termed "side" wipers, these wiper plates having comparatively thin upper engaging portions arranged to operate underneath the end plates 60 and to close inwardly over portions of the upper embraced by the end plates. The plates 80 are substantially coterminous in rearward extent with the end plates and are secured on arms 82 which are mounted on pivots 84 on the wiper support 50, these pivots being offset laterally of the support from the pivot 58 of the end wipers. Springs 86 connected at their opposite ends respectively to the arms 100 82 and to pins 88 on the ears 74 of the end wipers, tend to swing the arms outwardly and thus to hold the side wipers in open or retracted position, the outward limit of movement of the arms being determined by 105 their engagement with the pins 88.

For imparting operative movement to the side wipers 80 the machine has operating devices mounted upon arms 90 which are the usual arms provided heretofore in machines of this general type for carrying the side overlaying and tacking mechanisms, these arms being moved inward laterally of the shoe, as the arm 34 is swung rearwardly, by mechanism connected to the slide 110 38, as will be hereinafter described in greater detail. Mounted upon the lower ends of the arms 90 in place of the wiping and tacking mechanisms of prior machines are wiper operating members 92 the inner 115 edges of which are suitably shaped for engagement with the rounded outer edges of the wiper members 80, the members 92 being slidably mounted in guideways formed in plates 94 which are secured on the arms 120 90. Swiveled in a clamping plate 96 at one side of the plate 94 is a clamp screw 98 which extends through the plate 94 and also through a slot in the member 92, the end 125 of this screw being threaded in a clamping 130

plate 100 which engages the member 92. Threaded in the plate 100 is an adjusting screw 102 which is slotted for engagement with forked projections 104 at the outer end 5 of the member 92. By adjustment of the screws 102 the wiper operating members 92 may thus be positioned to vary the limit of inward movement of the different respective wiper plates 80 to conform to differences in the width and shape of different shoes, and in order to insure against accidental change in the adjustment the clamp screws 98 may be tightened to hold the members in adjusted position.

15 It will be understood that when the front arm 34 is swung toward the shoe, carrying the wipers 60 and 80 bodily lengthwise of the shoe, the pad 68 comes into engagement with the end of the shoe and stops the 20 movement of the bar 66 and the slide 62 while the movement of the arm and of the wiper support 50 continues. Such continued movement of the wiper support causes the levers 70 to fulcrum about their 25 points of engagement with the slide 62 and thus to swing the end wipers 60 laterally inward during their continued bodily movement lengthwise of the shoe. The connection between the bar 66 and the slide 62 30 permits the pad 68 to be adjusted to vary the time in the movement of the front arm when the lateral closing movement of the wipers is to begin. For the purposes in view the parts are preferably adjusted to 35 position the pad in advance of the edges of the wipers to cause the wipers to begin to close before they arrive at the edge of the shoe bottom and thus to be positioned in substantial conformity to the contour of 40 the edge at the beginning of their effective engagement with the shoe materials. As the end wipers are thus swung inwardly they carry the side wipers with them by reason of the engagement of the pins 88 with the 45 arms 82, the side wiper operating members 92 at the same time swinging inwardly with the arms 90 into position to engage the members 80 on their outer curved edge faces. As the wipers continue their opera- 50 tive movement lengthwise and laterally of the shoe they wipe the upper inwardly over the last bottom round the end and along the sides of the toe and gather the unsecured margin in a plurality of folds sub- 55 stantially as indicated in Fig. 8 wherein the end wipers are shown at the limit of their operative movement, this limit being determined by engagement of the levers 70 with a shoulder 109 on the wiper support 60 whereby further movement of the arm 34 and the wipers is stopped. It will be observed that at this stage in the operation the wiping edges of the thin side wiper plates 80 still occupy a retracted position 65 underneath the end wipers, and from this it

will be evident that the side wiper plates 80 do not become effective to perform their principal function until after the operative movement of the end wiper plates has been completed. By reference to Fig. 5 it will 70 be seen that the front portions of the edges of the end wiper plates are so formed as to extend substantially straight from side to side when the wipers are in their open position, this construction having particularly 75 in view the conditions encountered on a shoe having a wide and blunt toe, in order to provide sufficient room for the gathers or folds in the margin of the upper across the end of the toe. Experience has demonstrated that on shoes having comparatively 80 wide toes an outwardly convex or outwardly directed fold in the margin of the upper is formed substantially midway between the opposite sides of the toe by the relative lateral movement of the adjacent portions of these end wiper plates, and the wiper construction is such as to form an additional outwardly convex fold at each side of the middle fold and substantially in alinement 85 with it across the shoe. In order to assist 90 in determining the location of these additional folds, the straight front portions of the wiper edges end in curved notches or recesses 105 wherein the outwardly directed 95 folds form as the wipers move inwardly.

After the wipers have arrived in the position shown in Fig. 8 and the material has been gathered substantially in the manner indicated in said figure, continued movement of the operating members 92 effected by mechanism to be hereinafter more fully described, causes the side plates 80 to move relatively to the end plates to the position indicated in Fig. 9. By this movement the 100 wipers 80 operate to wipe still farther inwardly over portions of the materials embraced by the end wiper plates, and thus to insure the effective gathering of the material within a comparatively small area midway 105 between the opposite sides of the shoe. It will be evident that by reason of the location of the axes of the side plates 80 relatively to their wiping edges these plates 110 operate upon the material with a substantial component of movement forwardly toward the toe end of the shoe, these wipers thus having an important function in counteracting any tendency which the end plates 115 may have had, due to their large component of movement lengthwise of the shoe, to crowd the material backwardly along the sides and thus form objectionable wrinkles in or adjacent to the previously shaped portion back of the toe. In order to assist 120 still further in defining the location of the folds in the gathered material, the side plates 80 are notched as shown at 106, the foremost notches being arranged to aline 125 approximately with the notches 105 in the 130

end plates when the wipers are in closed position, and the rearmost notches being arranged to assist in forming an additional outwardly directed fold at each side of the 5 rear of the end folds.

One object in thus providing means for forming the folds in the gathered material in definite locations is to insure that the upper shall be fastened in definite relation to 10 the folds. In the construction shown the notches 105 and 106 serve additionally as recesses in which the securing tacks are driven, the tacking mechanism being definitely located with respect to the wipers, 15 as will be hereinafter explained, to drive the tacks at these points, and also to drive another tack midway between the two front corner tacks, as shown in Fig. 9. It will be observed that the several tacks are thus 20 driven substantially in line with the outwardly directed folds in the material, or at the lines of greatest convexity of the folds, and as thus driven they have an important function, especially where the shoe 25 is made of material such as felt, in preventing the material from springing up by reason of its natural resiliency after the wiping pressure is removed, which they would not perform as well if they were laterally 30 displaced to any substantial extent from the lines of the folds. As a result, the over-wiped margin of the upper is held substantially flat upon the bottom of the last in preparation for the subsequent upper trimming 35 operation whereby the surplus portion of the gathered margin is cut away, without the danger, which it is necessary to guard against carefully in shoes of this type, of cutting into the material too near the 40 edge of the last bottom.

The mechanism for driving the five tacks in the locations above described is carried by the front arm 34 which also carries the wiper mechanism. For driving the middle 45 tack, tacking mechanism similar to the construction shown in my earlier patent is provided, comprising a central tack holder 107 carried by the front arm 34 and a tack driver 108 which is operatively connected 50 by means of a forked member 110 to a driver bar 112 operated in the manner usual in machines of this type by a tack driving arm 114. Tacks are fed to the tack holder 107, as usual in such machines, from tack separating 55 mechanism 115 through a feed tube 116. Mounted on the arm 34 at opposite sides of the central tacker mechanism are additional tacker supports 118. At their outer ends the supports 118 are formed to provide cylindrical bearing portions recessed at their upper 60 ends for engagement with conical pivot studs 120 and at their lower ends for engagement with similar studs 122. By reference to Figs. 2 and 4 it will be seen that each of 65 the studs 122 carries a locking pin 124 which

by turning movement of the stud may be positioned to enter a slot 126 in the bracket 70 128 in which the stud is mounted, thus permitting the stud 122 to be retracted in such manner as to release the support 118 and 75 permit its removal. Carried by the tacker supports 118 are tack holders 130 and 132, these latter, as shown in Figs. 6 and 7, comprising complementary pairs of pivotally mounted fingers recessed to receive the tacks and normally pressed together by leaf springs 134 which embrace the fingers adjacent to their pivot points, the normal position of each pair of fingers being determined by a pin 136 in engagement in complementary 80 slots 138 in the fingers. It will be seen that the tack holders 130 and 132 are so arranged as to drive their tacks close together, the fingers being arranged to separate about axes 85 that extend lengthwise of the shoe to permit a substantially contiguous relation of the 90 holders, and that the tack holder 132 is directly in the rear of the holder 130, the different holders being relatively displaced in view of the rearwardly inclined relation of 95 the tackers to position their lower ends at substantially equal distances from the shoe bottom. The tack holder 130 is mounted on an integral portion 140 of the support 118 which extends outwardly to provide a passage 142 through which the tacks are fed. The tack holder 132, on the other hand, is mounted on a plate 144 which is secured by 100 screws 146 and 148 to the part 140 of the support and is likewise provided with a tack 105 passage 150. Adjacent portions of the parts 140 and 144 are channeled to provide a slide-way for driver blocks 152 which carry tack 110 drivers 154. For operating the drivers 154 of the two pairs of side tackers, the blocks 152 are connected by links 156 to ears 158 on brackets secured to the central tack driver 108. Tacks are fed to the tack passages 142 and 150 through feed tubes the lower portions 160 of which are flexible to permit the 115 lateral movement of the side tackers and the upper portions 162 of which are of substantially rigid material and loosely held in operative relation to the tack separator mechanism 115 by means of springs 164. At their lower ends the tube sections 162 are connected to the arm 34 to swing with the arm lengthwise of the shoe. These connections 120 serve to maintain the tack supply tubes in operative relation to the separator mechanism and the tackers in all positions of movement of the arm 34 and of the supports 118. In order to maintain the opposite pairs 125 of tackers above described initially in an out-of-the-way position in such manner that ample room may be afforded for presenting the shoe to the upper pulling means, and to position them in proper relation to the notches 105 and 106 in the wiper plates for 130 driving their tacks precisely in the required

- Locations at the end of the overwiping operation, the supports 118 are operatively connected to the side wiper plates 80. For this purpose each of the supports carries a member 166 provided with a guideway to receive a stud 168 mounted on the underlying wiper member 80, the member 166 being secured by the screws 148 to the plate 144 hereinbefore described.
- 10 The mechanism for imparting operative movement to the front wiper and tacker supporting arm 34 and to the two side wiper operating arms 90, and for actuating the tack driving mechanism, is shown in detail 15 in Fig. 10. As previously stated, operative rearward movement is imparted to the front arm 34 by means of a slide 38 which is operated by a pinion 40 (Fig. 1). The connection between the arm 34 and the slide 38 is a 20 yielding one, comprising spring plungers 170 supported in a bracket 172 secured to the slide and bearing upon inclined end faces formed on guide members 174 which are connected to the front arm. The slide 38 is 25 thus rendered effective to move the arm 34 rearwardly until resistance is encountered such that the spring plungers 170 yield and permit the bracket 172 to slide rearwardly along the guide members 174 as the member 30 38 continues its operative movement. Such abnormal resistance to continued movement of the arm 34 is encountered when the wiper operating levers 70 encounter the shoulder 109 on the wiper support, which prevents 35 continued relative movement between the support and the slide 62 on which the shoe engaging pad 68 is mounted. Similar yielding connections are provided for swinging the side arms 90 inwardly, comprising pivoted gear segments 176 operatively connected to the slide 38 and to slide members 178 which support spring plungers 180 in engagement with inclined faces on slides 182 which are operatively connected to the side 40 arms. The side arms are thus swung inwardly as the front arm 34 is swung toward the rear. In order to time the operation of the side wiper plates 80 relatively to that of the end plates as hereinbefore described, 45 provision is afforded for utilizing continued movement of the slide 38 after the movement of the arm 34 has been stopped to move the side arms and their wiper operating members 92 still farther inwardly and thus 50 to move the side wipers from the position of Fig. 8 to that of Fig. 9, the spring plungers 170 associated with the front arm yielding and sliding along the guides 174 to permit this operation to be effected. The 55 inner limit of movement of the side arms is determined by the engagement of lugs 184 on the arms with stop members 186 on the frame of the machine (Fig. 2). Movement of the slide 38 relatively to the arm 34 is also 60 utilized, as in prior machines of this general type, to trip the driver bar 112 and cause the tacks to be driven. For this purpose the bracket 172 carries a plate 188 which is arranged to engage under a plate 190 secured to the driver bar to hold the bar normally in its upraised position and is moved backwardly from under the latter plate to release the driver bar by the continued movement of the slide 38 after the front arm has arrived at its limit of movement. In the 65 present machine, of course, the tacks are not driven until after the operative movement of the side wipers 80 has been completed, the movement of the plate 188 relatively to the plate 190 before the driver bar is finally 70 tripped being sufficient to permit the side arms 90 to complete their wiper operating movement.
- 75 In order to insure the best results in the automatic toe lasting operation it is important that the shoe be positioned with substantial accuracy in predetermined relation to the wipers. It is contemplated that, as 80 in the use of prior machines of this general type, the lengthwise position of the shoe will 85 be determined by placing the toe end face of the last in engagement with the rear fixed toe gripper jaw when the work is presented to the machine, the shoe being subsequently 90 maintained in this position by the heel rest 95 95 100 105 110 115 120 125 130

- 130

plate 3 are adjustably movable lengthwise of the shoe under control of a pinion 194 which engages rack teeth on the member 2 and is arranged to be manually operated by 5 an adjusting device of any suitable construction the details of which are not herein illustrated.

In the operation of the machine on a shoe of the illustrative type in which the 10 toe end portion only has been left in unlasted and unsecured condition, the shoe is presented to the machine in the position indicated in Fig. 1 with the toe end face of the last in engagement with the rear toe 15 gripper jaw and with the materials on the bottom of the last at the opposite sides of the forepart in engagement with the two positioning studs 4, the unsecured margin of the upper at the toe end of the last projecting between the open toe gripper jaws. While holding the shoe in this position the operator actuates the starting clutch, whereupon the heel rest 12 with its positioning member 192 is moved up and locked against 20 the heel end portion of the shoe and the toe gripper closes upon and pulls a continuous section of the margin of the upper extending round the toe end of the last, assisted by a downward swinging movement of the 25 shoe rest, the machine then coming to a stop with the upper held under tension. If any adjustment of the upper relatively to the last or any change in the tensioning of the upper is necessary the operator is 30 now afforded an opportunity to make such change or adjustment by manipulation of the toe gripper in the manner characteristic of machines of this general type.

Upon the second actuation of the clutch, 40 the side clamping and supporting devices 14 are moved into operative relation to the shoe, and either immediately following the movement of these devices to operative position or after a subsequent rest in the cycle, 45 depending upon the number of stops provided on the controlling cam, the toe gripper is released by the slide 30 to the action of the overdraw springs 32 to cause it to pull the margin of the upper rearwardly over the bottom of the last and the front arm 50 34 is swung rearwardly by the slide 38 to carry the wipers and the tackers over the shoe. Before the edges of the end wipers 55 arrive in position adjacent to the edge of the shoe bottom the pad 68 engages the end of the shoe and in the continued movement of the arm 34 and the wiper support renders the end wiper operating means effective to close the wipers inward laterally 60 of the shoe, the wipers thus being closed into substantial conformity to the lateral contour of the shoe by the time they begin their overwiping action on the upper. At about the time when the end wipers become 65 effective to wipe the upper inwardly, the

front arm 34 engages the latch 48 on the toe gripper and causes the gripper to release the upper, the upper being held from objectionable reaction by the pressure of the incoming wipers and additionally by the 70 pressure of the pad 68 against the toe end of the shoe. After the end wipers have arrived at their limit of movement indicated in Fig. 8, the continued movement of the side arms 90 and the members 92 forces 75 the side wipers 80 to their limit of movement indicated in Fig. 9 to complete the overwiping and gathering operation in the manner and with the results hereinbefore more particularly described. As soon as the 80 side wipers have arrived at their limit of operative movement, the tack driving mechanism is actuated and the several tacks are driven substantially in the locations indicated by Fig. 9 to secure the upper in lasted 85 position. The parts then return to their starting positions and the shoe is released.

It will be evident that by reason of the inclination relatively to the plane of the shoe bottom of the axes about which the 90 side tacker supports 118 are swung, the opposite pairs of side tackers in their operative movement are carried downward toward the plane of the shoe bottom as well as inward laterally of the shoe. A desirable result of this arrangement is that sufficient space is afforded between the ends of the tack holders and the plane of the shoe bottom to permit the margin of the upper to be gathered and wiped inwardly by the 100 advancing wipers without interference by the tackers, the ends of the tack holders of course being maintained continuously substantially over the wiping edges of the end wiper plates. As the margin of the upper 105 is wiped inward progressively and flattened against the bottom of the last, the tack holders approach the plane of the last bottom until they arrive in position to drive the tacks in the relation to the gathered 110 folds of the upper illustrated by Fig. 9, wherein it will be seen that the foremost tacks are substantially aligned across the front of the gathered material and the tacks at each side aligned in a direction substantially parallel to the longitudinal median line of the shoe.

While the invention in herein illustrated with particular reference to the manufacture of shoes made of felt material in the 120 manner described, it will be understood that the invention is not limited in utility to the manufacture of this particular type of shoe or of shoes which are shaped to the last at the rear of the toe before the toe last- 125 ing is performed.

Having fully described my invention, what I claim as new and desire to secure by Letters Patent of the United States is:

1. In a machine of the class described, the 130

- combination with shoe positioning means, of means for gathering and wiping the margin of the upper inwardly round the end of the shoe, and additional wiping means constructed and arranged to extend lengthwise of the shoe along the gathered material and to move in a different direction and farther inward laterally of the shoe than said first wiping means to complete the overwiping and gathering operation after said first means has completed its operative movement.
2. In a machine of the class described, the combination with shoe positioning means, of means movable lengthwise and laterally of the shoe to gather and wipe the margin of the upper inwardly round the end of the shoe, and additional wiping means constructed and arranged to move subsequently farther inward than said first wiping means at the opposite sides of the same portion of the material with a component of movement lengthwise of the shoe in the reverse direction from said first means to complete the overwiping and gathering operation.
3. In a machine of the class described, the combination with shoe positioning means, of means for gathering and wiping the margin of the upper inwardly round the end of the shoe, and additional wiping means constructed and arranged to close inward laterally of the shoe between the shoe and said first means in engagement with portions of the upper embraced by said first means and to wipe over the upper for a substantially greater distance from the opposite side edges of the shoe bottom than the distance of movement of said first wiping means from the end face of the shoe.
4. In a machine of the class described, the combination with shoe positioning means, of means for gathering and wiping the margin of the upper inwardly round the end of the shoe, and additional wiping means movable subsequently inward in time relation to said first wiping means over portions of the material embraced by said first means to gather the unwiped margin of the upper within a substantially smaller area than the first means.
5. In a machine of the class described, the combination with shoe positioning means, of means for gathering and wiping the margin of the upper inwardly round the end of the shoe, and additional wiping means substantially coterminous with said first wiping means in rearward extent along the sides of the shoe and arranged to move in a different direction and farther inward laterally of the shoe than said first means to assist in the overwiping and gathering operation.
6. In a machine of the class described, the combination with shoe positioning means, of end embracing wipers, additional wipers arranged to move inwardly between said end wipers and the shoe and substantially coterminous with the end wipers in rearward extent along the sides of the shoe, and means automatically operative in time relation to the movement of said end wipers for moving said additional wipers inwardly beyond the inner edges of the end wipers.
7. In a machine of the class described, the combination with shoe positioning means, of end embracing wipers mounted for bodily movement lengthwise of the shoe and for relative closing movement laterally of the shoe, additional wipers arranged to move inwardly between said end wipers and the shoe and substantially coterminous with the end wipers in rearward extent along the sides of the shoe, said additional wipers being mounted to close over the shoe with a component of movement forwardly toward the end of the shoe, and means for moving said additional wipers inwardly beyond the inner edges of the end wipers.
8. In a machine of the class described, the combination with shoe positioning means, of end embracing wipers constructed and arranged to close inwardly for a substantially uniform distance from the edge of the shoe bottom round the end and along the sides of the end portion of the shoe, additional wipers arranged to close inward laterally of the shoe between the shoe and said end wipers, and means for moving said additional wipers over the shoe for a substantially greater distance from the edge of the shoe bottom than the end wipers.
9. In a machine of the class described, the combination with shoe positioning means, of end embracing wipers arranged to operate on the shoe, and additional wipers constructed and arranged to operate at the opposite sides of the shoe, after the end wipers have completed their operative movement, upon a portion of the stock embraced by said end wipers with wiping movements so directed as to counteract the tendency of the end wipers to displace the stock lengthwise of the shoe.
10. In a machine of the class described, the combination with shoe positioning means, of end embracing wipers mounted for bodily movement lengthwise of the shoe and for relative closing movement laterally of the shoe, and additional wipers arranged to move inward between said end wipers and the shoe beyond the inner edges of the end wipers after the end wipers have completed their operative movement with wiping movements differently directed laterally of the shoe from the movements of the end wipers to counteract the tendency of the end wipers to displace the stock lengthwise of the shoe.
11. In a machine of the class described, the combination with shoe positioning means,

of end embracing wipers mounted for closing movement over an end of the shoe, additional wipers mounted to move inward laterally of the shoe between the end wipers and the shoe with a component of movement outwardly toward said end of the shoe, and operating means constructed and arranged to move said additional wipers thus inwardly over the shoe in time relation to the end wipers and after the end wipers have arrived at their limit of operative movement.

12. In a machine of the class described, the combination with shoe positioning means, of end embracing wipers mounted for closing movement over the shoe, additional wipers arranged to move inward laterally of the shoe between said end wipers and the shoe, and power operating means automatically operative to move said additional wipers inwardly over the shoe beyond the inner edges of the end wipers after the end wipers have arrived at their limit of operative movement.

13. In a machine of the class described, the combination with shoe positioning means, of end embracing wipers mounted for closing movement over the shoe, additional wipers arranged to move inward laterally of the shoe between said end wipers and the shoe and positioned normally with their inner edges outwardly retracted beyond the inner edges of the end wipers, and operating means constructed and arranged to move said additional wipers inwardly beyond the inner edges of the end wipers after the end wipers have arrived at their limit of operative movement.

14. In a machine of the class described, the combination with shoe positioning means, of end embracing wipers mounted for bodily movement lengthwise of the shoe and for relative closing movement laterally of the shoe, side wipers mounted for movement lengthwise of the shoe with said end wipers and arranged to move inwardly between the end wipers and the shoe, and operating means constructed and arranged to move said side wipers inwardly over the shoe beyond the end wipers after the end wipers have arrived at their limit of operative movement lengthwise and laterally of the shoe.

15. In a machine of the class described, the combination with shoe positioning means, of end embracing wipers mounted for closing movement over an end of the shoe, side wipers constructed and arranged to move inwardly between the shoe and said end wipers with a component of movement outwardly toward said end of the shoe, and means for moving said side wipers thus inwardly beyond the inner edges of the end wipers after the end wipers have arrived at their limit of closing movement.

16. In a machine of the class described,

the combination with shoe positioning means, of end embracing wipers mounted for inward movement laterally of the shoe, additional wipers arranged to extend along the sides of the shoe between the shoe and said end wipers, and operating means constructed and arranged to move said end and side wipers inwardly together laterally of the shoe and then to continue the inward movement of the side wipers beyond the inner edges of the end wipers after the end wipers have arrived at their limit of inward movement.

17. In a machine of the class described, the combination with shoe positioning means, of end embracing wipers mounted for closing movement laterally of the shoe, additional wipers arranged to operate at the opposite sides of the end portion of the shoe, means for imparting closing movement to the end wipers, means for moving the side wipers inwardly with the end wipers, and additional means for imparting further inward movement to the side wipers to force them beyond the inner edges of the end wipers.

18. In a machine of the class described, the combination with shoe positioning means, of end embracing wipers mounted for closing movement laterally of the shoe, side wipers arranged to operate between the shoe and said end wipers at the opposite sides of the shoe, means for imparting closing movement to the end wipers, means for causing the side wipers to be moved inwardly by the end wipers, and means for imparting additional movement to the side wipers beyond the inner edges of the end wipers after the end wipers have arrived at their limit of operative movement.

19. In a machine of the class described, the combination with shoe positioning means, of end embracing wipers mounted for closing movement laterally of the shoe, side wipers arranged to operate between the shoe and said end wipers at the opposite sides of the shoe, means for imparting closing movement to the end wipers, means for positioning the side wipers normally with their wiping edges outwardly retracted beyond the wiping edges of the end wipers and for causing the side wipers to be moved inwardly with the end wipers, and means for moving the side wipers farther inwardly beyond the inner edges of the end wipers after the end wipers have arrived at their limit of closing movement.

20. In a machine of the class described, the combination with shoe positioning means, of a wiper support, end embracing wipers mounted on said support to swing inwardly over the shoe, means for operating said wipers, side wipers pivotally mounted on the support to swing inwardly over the opposite side portions of the stock embraced by the end wipers, connections between the

end wipers and the side wipers to cause the side wipers to be swung inwardly by the end wipers, and additional means for moving the side wipers farther inwardly beyond the inner edges of the end wipers.

21. In a machine of the class described, the combination with shoe positioning means, of end embracing wipers mounted to swing inwardly over the shoe each about an axis substantially midway between the opposite sides of the shoe, side wipers mounted to swing about axes positioned beyond the end of the shoe and spaced apart laterally of the shoe, means for operating said end wipers, and additional means for operating the side wipers in wiping engagement with the upper materials independently of the end wipers.

22. In a machine of the class described, the combination with shoe positioning means, of end embracing wipers mounted for swinging movement each about an axis substantially midway between the opposite sides of an end of the shoe, additional wipers mounted for closing movement inwardly between said end wipers and the shoe about axes so disposed as to impart to their wiping edges a component of movement outwardly toward said end of the shoe, and means for operatively moving said additional wipers thus inwardly after the end wipers have completed their operative movement.

23. In a machine of the class described, the combination with shoe positioning means, of end embracing wipers mounted for swinging movement each about an axis substantially midway between the opposite sides of an end of the shoe, additional wipers mounted for closing movement inwardly between said end wipers and the shoe about axes so disposed as to impart to their wiping edges a component of movement outwardly toward said end of the shoe, and means for moving said side wipers thus inwardly beyond the inner edges of the end wipers after the end wipers have completed their operative movement.

24. In a machine of the class described, the combination with shoe positioning means, of end embracing wipers mounted to swing laterally of the shoe each about an axis substantially midway between the opposite sides of the shoe, and additional wipers comprising comparatively thin plates arranged to slide inwardly between the end wipers and the shoe at the sides of the shoe and substantially coterminous in rearward extent with the end wipers, said additional wipers being mounted to swing about axes substantially opposite to the corners of the end portion of the shoe.

25. In a machine of the class described, the combination with shoe positioning means, of end embracing wipers, means arranged to be rendered operative by engage-

ment with the shoe to cause said wipers to close inwardly over the shoe, supplemental wipers arranged to operate along the opposite sides of the portion of the shoe embraced by said end wipers, and additional means for imparting operative movement to said supplemental wipers.

26. In a machine of the class described, the combination with shoe positioning means, of end embracing wipers, means arranged to be rendered operative by engagement with the shoe to cause said wipers to close inwardly over the shoe, supplemental wipers arranged to operate along the opposite sides of the portion of the shoe embraced by said end wipers, and means movable laterally of the shoe to operate said supplemental wipers independently of the end wipers.

27. In a machine of the class described, the combination with shoe positioning means, of end embracing wipers, means arranged to be rendered operative by engagement with the shoe to cause said wipers to close inwardly over the shoe, supplemental wipers arranged to move inwardly between the shoe and said end wipers at the opposite sides of the shoe, and additional operating means for moving said supplemental wipers inwardly over the shoe.

28. In a machine of the class described, the combination with shoe positioning means, of end embracing wipers, means arranged to be rendered operative by engagement with the shoe to cause said wipers to close inwardly over the shoe, supplemental wipers arranged to move inwardly between the shoe and said end wipers at the opposite sides of the shoe, and means constructed and arranged to impart to said supplemental wipers an operative movement independently of the end wipers.

29. In a machine of the class described, the combination with shoe positioning means, of end embracing wipers, means arranged to be rendered operative by engagement with the shoe to cause said wipers to close inwardly over the shoe, additional wipers arranged to move inwardly between the shoe and said end wipers at the opposite sides of the shoe, and means movable laterally of the shoe to force said additional wipers inwardly over the shoe after the end wipers have arrived at their limit of closing movement.

30. In a machine of the class described, the combination with shoe positioning means, of end embracing wipers, means arranged to be rendered operative by engagement with the shoe to close said wipers inwardly over the shoe, additional wipers arranged to move inwardly between the shoe and said end wipers at the opposite sides of the shoe, and means constructed and arranged to move said additional wipers

- inwardly beyond the inner edges of the end wipers after the end wipers have arrived at their limit of closing movement.
31. In a machine of the class described, the combination with shoe positioning means, of end embracing wipers, means arranged to be rendered operative by engagement with the shoe to cause said wipers to close inwardly over the shoe, additional wipers arranged to operate along the opposite sides of the portion of the shoe embraced by the end wipers, means for causing the side wipers to be closed inwardly with the end wipers, and additional means for imparting to the side wipers a further inward movement after the end wipers have arrived at their limit of closing movement.
32. In a machine of the class described, the combination with shoe positioning means, of end embracing wipers, means for closing said wipers inwardly over the shoe, additional wipers arranged to operate along the sides of the shoe on portions of the stock embraced by the end wipers, and means movable laterally of the shoe independently of the end wipers to force said additional wipers farther inwardly over the shoe than the end wipers.
33. In a machine of the class described, the combination with shoe positioning means, of end embracing wipers, a wiper support movable to carry said wipers lengthwise of the shoe, additional wipers carried by said support to operate at the opposite sides of the end portion of the shoe, means for closing the end wipers inwardly over the shoe, and means movable laterally of the shoe independently of the end wipers to force said additional wipers inwardly over the shoe beyond the inner edges of the end wipers.
34. In a machine of the class described, the combination with shoe positioning means, of end embracing wipers, a wiper support movable to carry said wipers lengthwise of the shoe, means for causing said wipers to be closed inward laterally of the shoe by said movement of the wiper support, side wipers also carried by said wiper support and mounted for movement laterally of the shoe, and additional operating means for the side wipers arranged to move inward laterally of the shoe and to move the side wipers relatively to the end wipers after the wiper support has arrived at its limit of operative movement.
35. In a machine of the class described, the combination with shoe positioning means, of means for gathering and wiping the margin of the upper inwardly round the end of the shoe, and additional wiping means arranged to operate subsequently upon the gathered margin of the upper and constructed to determine the location of folds in the margin.
36. In a machine of the class described, the combination with shoe positioning means, of means for gathering and wiping the margin of the upper inwardly round the end of the shoe, and additional wiping means constructed and arranged to move inwardly farther than said first means at the opposite sides of the gathered material and having wiping edges formed to determine the location of folds in the material.
37. In a machine of the class described, the combination with shoe positioning means, of means for gathering and wiping the margin of the upper inwardly round the end of the shoe, and additional wiping means constructed and arranged to move inwardly farther than said first means at the opposite sides of the gathered material with a component of movement outwardly toward the end of the shoe, said additional means being constructed to determine the location of folds in the gathered material.
38. In a machine of the class described, the combination with shoe positioning means, of end lasting wipers, means for closing said wipers inwardly over the shoe, said wipers being constructed and arranged to gather the margin of the upper in a plurality of forwardly directed folds in substantial alignment across the end of the shoe and an additional fold at each side positioned farther rearwardly and directed outwardly toward the side of the shoe, and means for driving a plurality of fastenings corresponding to the number of said folds and in determinate relation to the folds.
39. In a machine of the class described, the combination with shoe positioning means, of end embracing wipers mounted for relative closing movement laterally of the shoe and having wiping edges co-operating by oppositely directed movements to gather the margin of the upper in a forwardly directed fold substantially midway between the opposite sides of the shoe, said wipers having their wiping edges formed to produce also in the gathered margin of the upper an outwardly directed fold in a predetermined location at each side of said middle fold.
40. In a machine of the class described, the combination with shoe positioning means, of end embracing wipers mounted for relative closing movement laterally of the shoe, said wipers having wiping edges extending substantially straight in opposite directions from a point substantially midway between the opposite sides of the shoe, the straight portions of said edges being arranged to wipe the upper rearwardly from the end face of the shoe and terminating in recesses arranged to assist in determining the location of folds in the gathered margin of the upper.
41. In a machine of the class described,

the combination with shoe positioning means, of end embracing wipers mounted for relative closing movement laterally of the shoe, and arranged in overlapping relation at the end of the shoe, each of said wipers having its wiping edge formed with a substantially straight portion extending laterally of the shoe from the point where it meets the edge of the other wiper and terminating in a recess displaced laterally from the longitudinal median line of the shoe and another portion extending from said recess rearwardly and curved in substantial conformity to the curve of the edge of the shoe bottom.

42. In a machine of the class described, the combination with shoe positioning means, of end embracing wipers, and additional wipers movable between said end wipers and the shoe and arranged to close inward laterally of the shoe beyond the inner edges of the end wipers, said additional wipers having wiping edges provided with recesses to assist in determining the location of folds in the gathered margin of the upper.

43. In a machine of the class described, the combination with shoe positioning means, of end embracing wipers mounted for relative closing movement over the shoe and constructed and arranged to gather the margin of the upper in a plurality of forwardly directed folds, and additional wipers movable between the end wipers and the shoe and arranged to close inward laterally of the shoe beyond the inner edges of said end wipers, said additional wipers having their wiping edges recessed to form outwardly directed folds in the margin of the upper in predetermined locations at the rear of said first mentioned folds.

44. In a machine of the class described, the combination with shoe positioning means, of end embracing wipers mounted for relative closing movement laterally of the shoe, said wipers having recesses in their wiping edges to determine the location of folds in the gathered margin of the upper, and additional wipers movable between said end wipers and the shoe and arranged to close inward laterally of the shoe beyond the inner edges of the end wipers, said additional wipers having their wiping edges provided with recesses arranged to determine the location of additional folds at the rear of the folds formed by the end wipers.

45. In a machine of the class described, the combination with shoe positioning means, of end embracing wipers mounted for relative closing movement laterally of the shoe, said wipers having recesses in their wiping edges to determine the location of folds in the gathered margin of the upper, and additional wipers movable between said

end wipers and the shoe and arranged to close inward laterally of the shoe beyond the inner edges of the end wipers, said additional wipers having their wiping edges provided with recesses arranged to aline substantially with the recesses of the end wipers when the wipers are at their limit of closing movement and with additional recesses at the rear of said first-mentioned recesses to determine the location of additional folds in the margin of the upper.

46. In a machine of the class described, the combination with shoe positioning means, of end embracing wipers mounted for relative closing movement laterally of the shoe, said wipers having their wiping edges formed with recesses to determine the location of folds in the gathered margin of the upper, additional wipers movable between said end wipers and the shoe and arranged to close inwardly beyond the inner edges of said end wipers, said additional wipers having recesses in their wiping edges arranged to determine the location of folds at the rear of said first folds, and operating means constructed and arranged to move said additional wipers farther inwardly after the end wipers have arrived at their limit of closing movement.

47. In a machine of the class described, the combination with shoe positioning means, of means for gathering and wiping the margin of the upper inwardly round the end of the shoe, means for inserting a plurality of fastenings substantially at the front of the gathered margin of the upper, and additional means arranged to insert other fastenings at the opposite sides of the gathered margin farther rearwardly and farther inwardly from the corresponding portions of the edge of the shoe bottom than said front fastenings.

48. In a machine of the class described, the combination with shoe positioning means, of means for gathering and wiping the margin of the upper inwardly round the end of the shoe, and means for fastening the upper in lasted position including devices constructed and arranged to insert a plurality of fastenings at each side of the gathered margin and alined in substantially parallel relation to the longitudinal median line of the shoe.

49. In a machine of the class described, the combination with shoe positioning means, of means for gathering and wiping the margin of the upper inwardly round the end of the shoe constructed and arranged to form in predetermined locations a plurality of folds in the margin directed forwardly toward the end of the shoe and additional folds located farther rearwardly and directed outwardly toward the sides of the shoe, and means for inserting fastenings

substantially in line with the different respective folds to hold the upper in lasted position.

50. In a machine of the class described, the combination with shoe positioning means, of means for gathering and wiping the margin of the upper inwardly round the end of the shoe constructed and arranged to form in predetermined locations in the gathered margin a plurality of folds directed forwardly toward the end of the shoe and additional folds positioned farther rearwardly and directed outwardly toward the sides of the shoe, means for inserting a plurality of fastenings substantially between said forwardly directed folds and the end of the shoe, and means for inserting additional fastenings in locations substantially between said rear folds and the sides of the shoe.

51. In a machine of the class described, the combination with shoe positioning means, of end embracing wipers constructed to form outwardly directed folds in the margin of the upper in predetermined relation to the wipers, and upper fastening means arranged in such relation to the wipers as to insert fastenings substantially in line with said folds.

52. In a machine of the class described, the combination with shoe positioning means, of end embracing wipers having wiping edges provided with recesses so formed as to determine the location of outwardly directed folds in the margin of the upper, and upper fastening means constructed and arranged to insert fastenings in said recesses substantially in line with said folds.

53. In a machine of the class described, the combination with shoe positioning means, of means for gathering and wiping the margin of the upper inwardly round the end of the shoe comprising wipers having wiping edges formed to determine the location of outwardly directed folds in the gathered margin in spaced locations lengthwise of the shoe, and upper fastening means arranged to be positioned by said wipers for inserting fastenings in predetermined relation to said outwardly directed folds.

54. In a machine of the class described, the combination with shoe positioning means, of means for gathering and wiping the margin of the upper inwardly round the end of the shoe comprising wipers having wiping edges recessed to determine the location of a plurality of outwardly directed folds in the gathered margin, and upper fastening means arranged to be positioned by said wipers for inserting fastenings substantially in line with said folds.

55. In a machine of the class described, the combination with shoe positioning means, of end embracing wipers having

wiping edges recessed to determine the location of folds in the gathered margin of the upper, additional wipers movable laterally inward over the end portion of the shoe and having wiping edges recessed to determine the location of additional folds at the rear of said first folds, and upper fastening means arranged to be positioned by the wipers for inserting fastenings in predetermined relation to the several folds. 70 75

56. In a machine of the class described, the combination with shoe positioning means, of means for gathering and wiping the margin of the upper inwardly round the end of the shoe comprising wipers mounted for movement laterally of the shoe and having wiping edges recessed to form in the margin of the upper outwardly directed folds spaced apart lengthwise of the shoe, and upper fastening devices arranged to move laterally of the shoe with said wipers and to insert fastenings in predetermined relation to said folds. 80 85

57. In a machine of the class described, the combination with shoe positioning means, of end embracing wipers, additional wipers arranged to move inwardly between the shoe and said end wipers to complete the overwiping operation, and upper fastening devices arranged to be moved inwardly over the shoe by said additional wipers. 90 95

58. In a machine of the class described, the combination with shoe positioning means, of end embracing wipers, additional wipers arranged to move inwardly between the shoe and said first wipers to complete the overwiping operation, and upper fastening means comprising a pair of tackers associated with each of said additional wipers and arranged to be moved inwardly by said wipers for driving tacks in predetermined relation to the wipers. 100 105

59. In a machine of the class described, the combination with shoe positioning means, of end embracing wipers mounted for relative closing movement laterally of the shoe, additional wipers mounted to move inwardly between said end wipers and the shoe at the opposite sides of the end portion of the shoe, means for moving said additional wipers inwardly beyond the inner edges of the end wipers after the end wipers have completed their closing movement, upper fastening devices arranged to be positioned by said additional wipers, and means for operating said devices to drive the fastenings after said last named wipers have completed their operative movement. 110 115

60. In a machine of the class described, the combination with shoe positioning means, of end embracing wipers, side wipers mounted to swing laterally of the shoe about axes transverse to the plane of the shoe bottom, side tackers, and means connecting said tackers to the side wipers to cause them to 120 125 130

be moved inwardly over the shoe with said wipers.

61. In a machine of the class described, the combination with shoe positioning means, of end lasting wipers, a wiper support movable to carry said wipers lengthwise of the shoe, and upper fastening means carried by said support and arranged to insert a plurality of fastenings in substantial alignment across the end of the shoe and additional fastenings located farther rearwardly at the opposite sides of the gathered margin of the upper.

62. In a machine of the class described, the combination with shoe positioning means, of end embracing wipers, a wiper support movable to carry said wipers lengthwise of the shoe, additional wipers carried by said support and movable relatively to said end wipers, and upper fastening means also carried by said support and arranged to be positioned by said additional wipers in their movement relatively to the end wipers.

63. In a machine of the class described, the combination with shoe positioning means, of end embracing wipers, additional wipers mounted to move inwardly between said end wipers and the shoe at opposite sides of the shoe, a wiper support movable to carry the several wipers lengthwise of the shoe, means for moving said additional wipers inwardly after said support has completed its movement lengthwise of the shoe, and upper fastening means also carried by said support and comprising fastening devices arranged to be positioned by the movement of said additional wipers.

64. In a machine of the class described, the combination with shoe positioning means, of a wiper support mounted for movement lengthwise of the shoe, wipers mounted on said support to swing over the shoe about axes spaced from each other laterally of the shoe, and upper fastening devices also mounted on said support and connected to said wipers to be positioned laterally of the shoe by the wipers.

65. In a machine of the class described, the combination with shoe positioning means, of a wiper support mounted for movement lengthwise of the shoe, wipers on said support, a tacker carried by said support and arranged to drive a tack substantially midway between the opposite sides of the shoe, and a pair of additional tackers on said wiper support at each side of said first-named tacker mounted for positioning movement laterally of the shoe and relatively to said first tacker.

66. In a machine of the class described, the combination with shoe positioning means, of wipers mounted for closing movement laterally of the shoe, a wiper support movable to carry said wipers lengthwise of

the shoe, a tacker carried by said support and arranged to drive a tack substantially midway between the opposite sides of the shoe, and additional tackers arranged to drive tacks in spaced locations lengthwise of the shoe at the opposite sides and connected to the wipers for positioning movement laterally of the shoe and relatively to said first tacker.

67. In a machine of the class described, the combination with shoe positioning means, of end embracing wipers, a wiper support movable to carry said wipers lengthwise of the shoe, additional wipers mounted on said support for movement laterally of the shoe and relatively to said end wipers, upper fastening devices also mounted on said support to swing laterally of the shoe, and connections between said devices and the additional wipers to cause said devices to move laterally of the shoe with said wipers.

68. In a machine of the class described, the combination with shoe positioning means, of end lasting wipers and upper fastening devices supported beyond the end of the shoe for swinging movement laterally of the shoe and arranged to insert a plurality of fastenings in spaced locations lengthwise of the shoe.

69. In a machine of the class described, the combination with shoe positioning means, of end lasting wipers, and upper fastening means comprising a pair of tackers at each side of the shoe mounted to swing laterally of the shoe about axes inclined to the plane of the shoe bottom into position for driving the tacks in spaced locations lengthwise of the shoe.

70. In a machine of the class described, the combination with shoe positioning means, of end lasting wipers mounted for closing movement laterally of the shoe, upper fastening means comprising a pair of tackers at each side of the shoe mounted to swing laterally of the shoe about axes inclined to the plane of the shoe bottom, and means connecting said tackers to the wipers to cause the tackers to swing inwardly with the wipers.

71. In a machine of the class described, the combination with shoe positioning means, of means for working the upper inwardly over the shoe bottom, and upper fastening means comprising tacking devices mounted for movement laterally of the shoe about axes transverse to the plane of the shoe bottom, said devices having oppositely disposed recesses, and pivot studs engaging in said recesses to support the tackers for swinging movement.

72. In a machine of the class described, the combination with shoe positioning means, of means for working the upper inwardly over the shoe bottom, and upper

fastening means comprising tacking devices supported for swinging movement laterally of the shoe about axes transverse to the plane of the shoe bottom, the supports for 5 said devices comprising pivot studs movable to permit detachment of the devices.

73. In a machine of the class described, the combination with means for working an upper over a last, of tacking devices 10 mounted beyond the end of the shoe to swing laterally of the shoe into tacking position and comprising tack holders and drivers arranged for driving tacks in spaced locations lengthwise of the shoe, said tackers 15 being inclined rearwardly toward the plane of the shoe bottom with the tack holders relatively displaced to position them at substantially equal distances from said plane.

74. In a machine of the class described, 20 the combination with means for working an upper over a last, of tack holders arranged in closely adjacent relation to each other and each comprising a pair of tack holding fingers mounted to swing relatively about an 25 axis extending lengthwise of the adjacent portion of the edge of the shoe bottom, and tack drivers arranged in co-operative relation to said holders.

75. In a machine of the class described, 30 the combination with means for working an upper over a last, of upper fastening means comprising a tack holder having co-operating fingers mounted to swing relatively about an axis substantially perpendicular to 35 the direction of driving movement of the tack, a spring embracing said fingers to hold them normally in tack holding position, and a driver arranged to operate upon the tack in said holder.

76. In a machine of the class described, 40 the combination with means for working an upper over the end portion of a last, of tackers mounted for movement laterally of the end portion of the shoe at its opposite 45 sides into tack driving position and comprising tack holders and drivers, a driver bar, and link connections between said bar and the drivers for operating the drivers.

77. In a machine of the class described, 50 the combination with means for working an upper over the end portion of a last, of upper fastening means comprising a central tack holder and driver and a driver bar connected to said driver, additional tackers 55 comprising tack holders and drivers movable laterally of the shoe and relatively to the central tacker into tack driving position, and link connections between said last named drivers and the central tack driving 60 means for operating said drivers.

78. In a machine of the class described, 65 the combination with means for working an upper over the end portion of a last, of upper fastening means comprising a central tacker substantially fixed against movement

laterally of the shoe and a pair of additional tackers at each side movable laterally of the shoe and relatively to said central tacker into tack driving position, each of the several tackers comprising a tack holder and a 70 driver, a driver bar common to all the drivers, and connections between said bar and the several drivers for operating said drivers in unison.

79. In a machine of the class described, 75 the combination with means for working an upper over a last, of upper fastening means comprising a central tack driver and a pair of additional drivers at each side of the end portion of the shoe mounted for positioning movement laterally of the shoe and relatively to said central driver, means for operating the central driver, and means comprising links pivotally connected to the respective pairs of additional drivers to cause them to receive operative movement from the central driver while permitting them to move laterally of the shoe into and out of tacking position.

80. In a machine of the class described, 90 the combination with shoe positioning means, of a wiper support mounted for movement relatively to the shoe, a wiper on said support, a tacker also mounted on said support, and tack supplying means comprising a tack separator and a conduit connected at one end to said tacker to move with it into and out of tacking position, said conduit being loosely connected at its other end to said separator to permit it to move with the tacker without displacement from operative relation to the separator.

81. In a machine of the class described, 95 the combination with shoe positioning means, of a wiper support mounted for movement relatively to the shoe, a wiper on said support, a tacker also mounted on said support, tack supplying means comprising a conduit connected at one end to said tacker for movement with it into and out of tacking position, a tack separator, and spring means yieldingly holding the other end of said conduit in operative relation to said separator in all positions of movement of the conduit.

82. In a machine of the class described, 110 the combination with shoe positioning means, of a wiper support mounted for movement lengthwise of the shoe, a wiper on said support, a tacker also mounted on said support for movement lengthwise of the shoe and for movement also relatively to the support in directions laterally of the shoe, a tack separator, and a tack conduit having a substantially rigid upper portion leading 115 from said separator and connected at its lower end to said support to be swung by the support in its movement lengthwise of the shoe and a lower flexible portion to maintain an operative connection with the 120 125

tacker while permitting the tacker to swing laterally of the shoe.

83. In a machine of the class described, the combination with means for working an upper over a last, of means having a three-point bearing on the shoe bottom to position the shoe in operative relation to said overworking means, said bearing points being located respectively at the opposite sides of the forepart and at the heel end portion of the shoe and relatively adjustable to determine the position of the shoe with respect to movement about its longitudinal axis.

84. In a machine of the class described, the combination with means for working an upper over a last, of members arranged to engage the bottom of the shoe at opposite sides of the forepart and relatively adjustable to determine the lateral inclination of the shoe, and an additional member arranged to engage the shoe bottom at the heel end portion to determine the lengthwise inclination of the shoe.

85. In a machine of the class described, the combination with means for working an upper over a last, of work positioning members arranged to engage the shoe bottom at opposite sides of the forepart and relatively adjustable to determine the lateral inclination of the shoe, and an additional member arranged to engage the shoe bottom at the heel end portion to determine the lengthwise inclination of the shoe, said forepart and heel positioning members being relatively adjustable to vary the lengthwise inclination of the shoe.

86. In a machine of the class described the combination with toe lasting wipers and power operated means for moving said wipers over a shoe, of means constructed and arranged to engage the bottom of the shoe at three points only located respectively at the opposite sides of the forepart and at the heel end portion to determine the position of the shoe in relation to said wipers.

87. In a machine of the class described, the combination with toe lasting wipers and power operated means for moving said wipers over a shoe, of means constructed and arranged to engage the bottom of the shoe at three points only located respectively at the opposite sides of the forepart and at the heel end portion to determine the position of the shoe in relation to said wipers, said shoe engaging means being adjustable to vary the lateral and lengthwise inclination of the shoe.

88. In a machine of the class described, the combination with toe lasting wipers and power operated means for moving said wipers over a shoe, of a shoe rest comprising members arranged to engage the bottom of the shoe at opposite sides of the forepart and relatively adjustable to deter-

mine the lateral inclination of the shoe, and additional means arranged to engage the bottom of the shoe at the heel end portion to determine its lengthwise inclination.

89. In a machine of the class described, the combination with toe lasting wipers and power operated means for moving said wipers over a shoe, of means bearing on the bottom of the forepart of the shoe at two points only spaced laterally of the shoe to determine the lateral inclination of the shoe, a heel rest arranged to embrace the heel end portion of the shoe, and means on said heel rest arranged to project over the bottom of the heel end of the shoe to determine the lengthwise inclination of the shoe.

90. In a machine of the class described, the combination with toe lasting wipers and power operated means for moving said wipers over a shoe, of a shoe bottom rest comprising a plate having studs arranged to engage the bottom of the shoe at opposite sides of the forepart and adjustable to determine the lateral inclination of the shoe, said plate also being adjustably movable in directions transverse to the plane of the shoe bottom, and a heel rest having means arranged to project over the bottom of the heel end portion of the shoe to determine the lengthwise inclination of the shoe.

91. In a machine of the class described, the combination with shoe positioning means, of means for gathering and wiping the margin of the upper inwardly at the end and the sides of the toe of the shoe comprising end embracing wipers and supplemental side wiper members and operating mechanism constructed and arranged to wipe the upper farther inwardly from the edge of the shoe bottom at the sides of the toe than at the end of the toe.

92. In a machine of the class described, the combination with shoe positioning means, of end embracing wipers for gathering and wiping the margin of the upper inwardly round the toe of the shoe, supplemental wipers movable inwardly between said end wipers and the shoe at the sides of the toe beyond the inner edges of the end wipers, and operating mechanism for imparting to said end embracing wipers and supplemental wipers determinate movements to wipe the upper farther inwardly from the edge of the shoe bottom at the sides of the toe than at the end of the toe.

93. In a machine of the class described, the combination with shoe positioning means, of means for gathering and wiping the margin of the upper inwardly around the toe of the shoe and farther inwardly at the sides of the toe than at the end of the toe, and fastening mechanism automatically operative to insert upper securing fasten-

ings at the end and at the sides of the gathered material with the side fastenings located farther inwardly from the corresponding portions of the edge of the shoe bottom than the end fastenings.

94. In a machine of the class described, the combination with shoe positioning means, of means for gathering and wiping the margin of the upper inwardly around the toe of the shoe comprising end embracing wiper plates and supplemental wiper plates movable inwardly between the shoe and said end plates at the sides of the toe, and operating members movable laterally of the shoe to operate said supplemental wiper plates, said operating members being adjustable to vary the limits of inward movement of said supplemental plates.

95. A machine of the class described having, in combination, means for gripping and pulling the upper of a shoe at the end of the toe only while leaving free the margin of the upper at the sides of the shoe, means for gathering and wiping the margin of the upper inwardly at the end and the sides of the toe comprising end embracing wiper plates and supplemental wiper plates mov-

able inwardly at the sides of the toe between the shoe and said end plates, and operating means for said supplemental wiper plates comprising side arms movable laterally of the shoe and having means thereon for pushing the supplemental plates inwardly over the shoe.

96. In a machine of the class described, the combination with means for pulling an upper over a last, of end embracing wiper plates for gathering and wiping the margin of the upper inwardly round the toe of the shoe, supplemental wiper plates arranged to operate at the sides of the toe, and operating means for said supplemental wiper plates comprising side arms movable laterally of the shoe and having thereon operating members for forcing said plates inwardly over the shoe, said operating members being adjustable relatively to the side arms each independently of the other to determine different limits of movement of the respective supplemental wiper plates.

In testimony whereof I have signed my name to this specification.

BERNHARDT JORGENSEN.
